Inventor
WILLIAM H. BROWN
By Albert C. Bell
Attorney.

UNITED STATES PATENT OFFICE.

WILLIAM H. BROWN, OF CHICAGO, ILLINOIS.

CURTAIN BRACKET.

Application filed May 11, 1923. Serial No. 638,215.

To all whom it may concern:

Be it known that I, WILLIAM H. BROWN, a citizen of the United States, residing at Chicago, in the county of Cook and State of Illinois, have invented a new and useful Improvement in Curtain Brackets, of which the following is a specification.

My invention relates to an improved form of curtain bracket by which the bracket may be swung in its support and retained in desired angular position relatively to a door or window opening without the use of special locking devices and without requiring anything but a turning movement of the bracket to move it from one angular position to another. My invention is characterized by extreme simplicity of construction and effectiveness of operation and it is adapted particularly for suspending curtains across window or door openings or suspending other articles where it is desired to hold the bracket in a certain angular position, for example parallel with the wall upon which the bracket is supported, and yet permit a ready turning of the bracket with the curtain or article suspended therefrom, to some other position and at the same time retain the bracket and suspended curtain or article in the said parallel relation and, if desired, other angular relations, without using additional devices for retaining the bracket in desired angular position, the retaining arrangement resulting from the confirmation of the bearing surfaces themselves of the bracket and the support.

My invention will best be understood by reference to the accompanying drawings showing a preferred embodiment thereof, in which—

Fig. 1 shows in perspective view a support for use in connection with my invention.

Fig. 2 is a top view of the support shown in Fig. 1 with a portion of the bracket therein,

Fig. 3 shows in front elevation the support mounted in place on a suitable supporting member with the bracket in place in the support, and

Fig. 4 shows in plan view to a reduced scale, the arrangement of a pair of supports and brackets used adjacent an opening in a wall, for example a window opening.

Similar numerals refer to similar parts throughout the several views.

As shown in Fig. 3, my construction consists of a support 10 having a base portion to be secured to a vertical surface, for example a part of a window or door frame 11, by suitable means such as screw, and from the upper and lower portion of the base, horizontal flanges 10^a and 10^b project through which openings are made to receive the vertical portion of 12^a of a bent bracket 12, the other portion 12^b of which projects horizontally, that is substantially at right angles to the portion 12^a. The portion 12^a as indicated in Fig. 3, is of circular cross section and is provided at its lower end with a flattened surface 14 on its side away from the direction of extension of the portion 12^b, and at its upper end it is provided on its opposite side, that is to say on its side in the direction of the extension of the portion 12^b, with a similar flattened surface 15, said flattened surfaces being for the purpose of engaging the bearing surfaces in the flanges 10^a and 10^b. While the bracket 12 may be of any desired conformation and cross section, as long as the angular relation between its portions is maintained and the flattened surfaces referred to are employed, it is generally convenient to make the bracket of the telescoping type, by providing an outer extension 16 making a sliding fit with the portion 12^b and preferably provided with a knob 17 or other enlargement on its outer end to hold the curtain or supported article in place on the bracket. By this means the effective length of the bracket may be changed as desired; the part 16 may be prevented from rotating on the portion 12^b in any suitable manner, well known in the art. It will be understood of course, that the telescoping construction need not be used where a non-adjustable bracket is desired, in which case the portion 12^b is made of a length to directly support the curtain or other article.

As shown in Figs. 1 and 2, the opening 18 provided to be engaged by the flattened surface 15, is provided with a plurality of flattened surfaces any one of which may engage the flattened surface 15, depending upon the angular position of the bracket 12, and the opening 19 is correspondingly provided with flattened surfaces for engaging the flattened surface 14 on the portion 12^a, the only difference being that the flattened surfaces on the bearing surface of the opening 19 are opposite to the corresponding

flattened surfaces of the opening 18, so that for any angular position of the bracket for which it is retained against angular movement, it is engaged by one flattened surface 5 of the bearing portion of the opening 18 and an opposite flattened surface of the bearing surface of the opening 19.

As a result of the construction described the weight of the bracket extending outwardly from the support 10 and the weight 10 of the curtain or article supported by the bracket tend to hold the flattened surface 15 against the corresponding flattened surface of the opening 18 and at the same time 15 hold the flattened surface 14 against the corresponding flattened surface of the opening 19, and the co-operation of the several flattened surfaces referred to, results in holding the bracket against free angular 20 movement in the support 10. When it is desired to rotate the bracket in the support, sufficient force must be exerted upon the bracket in a turning direction, to slightly lift its outer end to permit the flattened 25 surfaces 14 and 15 to move from engagement with the flattened surfaces of the support engaged thereby, into engagement with the next pair of flattened surfaces of the openings, in the direction 30 of rotation of the bracket. It will be observed however, that this angular movement of the bracket requires no lifting of the portion 12^a in the support 10 and that, therefore, there is small effort required to 35 turn the bracket in the support 10, compared with what would be required if it were necessary to lift the entire bracket in the support 10, and furthermore, that there is no uncertainty about the vertical portion 40 of the bracket occupying a proper vertical position in the support 10 at all times, since it always remains in a certain vertical position in the support, determined, either by the resting of the portion 12^b on the flange 45 10^a, or the resting of the shoulder on the portion 12^a adjacent the flattened surface 14, on the upper surface of the flange 10^b, and that the shoulders adjacent the flattened surfaces 14 and 15 serve to prevent vertical 50 displacement of the portion 12^a in the support 10. The effect therefore is an interlocking relation between the bracket and the support for any one of a plurality of angular positions, without the use of auxiliary devices of any kind and without in any 55 way complicating the construction of the support or of the bracket itself. The openings 18 and 19 are preferably of such a size as to just clear the vertical portion 12^a of the bracket as it is turned from one position to another in the support 10.

In Fig. 4, I show two brackets 12^a, 12^b mounted in supports 10^a, 10^b on a window casing 11, so that the curtain supported by 60 each bracket will cover substantially half of

the window opening. It will be understood however, that the brackets may have any desired size or proportion and may be used either in pairs as shown in Fig. 4 or singly as desired.

It will be noted that my improved construction is of extreme simplicity, that it is effective in operation and cannot readily get out of order.

While I have shown my invention in the 75 particular embodiment above described, it will be understood that I do not limit myself to this exact construction as I may employ equivalents known to the art at the time of the filing of this application without departing from the scope of the appended claims.

What I claim is:

1. In a device of the class described, the combination of a support having outwardly 85 extending flanges provided with flat sided apertures extending through them, the flattened sides of said apertures being in angular alignment with each other and on opposite sides of the axis of said apertures, and a bent bracket provided with flattened surfaces on its opposite sides for engaging the flattened surfaces of said apertures.

2. In a device of the class described, the combination of a support provided with outwardly extending flanges having apertures extending therethrough in alignment with each other, and a bracket having a vertically extending portion in said apertures, 95 said apertures and the sides of said vertically extending portion having cooperating surfaces tending to hold said bracket against free rotation in said apertures.

3. In a device of the class described, the combination of a supporting means having 105 apertures in alignment with each other, and a bracket having a vertically extending portion in said apertures, said vertically extending portion having a flattened surface on its side engaging one of said apertures 110 and said engaged aperture having a corresponding flattened bearing surface for holding the bracket against free turning movement in said apertures.

4. In a device of the class described, the 115 combination of supporting means having apertures in alignment with each other, and a bracket having a vertically extending portion in said apertures, said bracket having flattened surfaces on its sides in opposed relation to each other engaging said apertures and said apertures having a pair of corresponding flattened surfaces for simultaneously engaging the flattened surfaces on said bracket.

5. In a device of the class described, the combination of a supporting means having a pair of apertures in alignment with each other, and a bracket having a vertically extending portion in said apertures, said ver- 130

- tically extending portion having flattened surfaces in opposed relation on its sides for engaging said apertures and said apertures having a plurality of pairs of flattened surfaces for engaging the flattened surfaces on said vertical portion for a plurality of angular positions of the bracket in said supporting means, each pair of flattened surfaces of said apertures comprising a flattened surface on one side of one aperture and a corresponding flattened surface on the other side of the other aperture.
6. In a device of the class described, the combination of a support having outwardly extending flanges provided with flat sided apertures extending through them, the flattened sides of said apertures being in angular alignment with each other and on opposite sides of the axis of said apertures, and a bent bracket provided with flattened surfaces on its opposite sides for engaging the flattened surfaces of said apertures, said bracket having shoulders adjacent to its flattened surfaces preventing movement of said bracket longitudinally in said apertures.
7. In a device of the class described, the combination of a support provided with outwardly extending flanges having openings extending therethrough in alignment with each other, and a bracket having a vertically extending portion in said apertures, said apertures and the sides of said vertically extending portion having co-operating surfaces tending to hold said curtain rod against free rotation in said apertures, said bracket having shoulders adjacent to its said co-operating surfaces preventing movement of said bracket longitudinally in said apertures.
8. In a device of the class described, the combination of a supporting means having apertures in alignment with each other, and a bracket having a vertically extending portion in said apertures, said vertically extending portion having a flattened surface
- on its side engaging one of said apertures and said engaged aperture having a corresponding flattened bearing surface for holding the bracket against free turning movement in said apertures, said vertically extending portion having a shoulder adjacent to its flattened surface preventing movement of said bracket longitudinally in said apertures.
9. In a device of the class described, the combination of supporting means having apertures in alignment with each other, and a bracket having a vertically extending portion in said apertures, said bracket having flattened surfaces on its sides in opposed relation to each other engaging said apertures, and said apertures having a pair of corresponding flattened surfaces for simultaneously engaging the flattened surfaces on said bracket, said vertical portion having shoulders adjacent its flattened surfaces preventing vertical movement of said bracket in said apertures.
10. In a device of the class described, the combination of a supporting means having a pair of apertures in alignment with each other, and a bracket having a vertically extending portion in said apertures, said vertically extending portion having flattened surfaces in opposed relation on its sides for engaging said apertures and said apertures having a plurality of pairs of flattened surfaces for engaging the flattened surfaces on said vertical portion for a plurality of angular positions of the bracket in said supporting means, each pair of flattened surfaces of said apertures comprising a flattened surface on one side of one aperture and a corresponding flattened surface on the other side of the other aperture, said vertical portion having shoulders adjacent its flattened surfaces preventing vertical movement of said bracket in said apertures.
- In witness whereof, I hereunto subscribe my name this 9th day of May, A. D. 1923.
- WILLIAM H. BROWN.
